ROOM AIR CONDITIONER

Robert W. Blee, Louisville, Ky., assignor to General Electric Company, a corporation of New York

Filed July 1, 1958, Ser. No. 51,619

Term of patent 14 years

(Cl. D62—4)

The figure is a perspective of a room air conditioner embodying my new design. The right side of said room air conditioner is the same in appearance as the left side shown in the drawing. The dominant features of the design reside in the portions shown in full line. The rear is substantially plain.

I claim:

The ornamental design for a room air conditioner, substantially as shown and described.
